UNITED STATES PATENT OFFICE.

JOHN JACOB PFENNINGER, OF ST. LOUIS, MISSOURI.

DESIGN FOR A DIE FOR CUTTING DOUGH.

SPECIFICATION forming part of Design No. 22,532, dated June 13, 1893.

Application filed March 3, 1893. Serial No. 464,623. Term of patent 14 years.

To all whom it may concern:

Be it known that I, JOHN JACOB PFENNINGER, a citizen of the United States, residing at St. Louis, State of Missouri, have invented and produced a new and original Design for Dies for Cutting Dough, of which the following is a specification, reference being had to the accompanying drawing, showing a part thereof.

10 The figure represents a perspective view of the die.

The leading feature of the design is a series of circles one within the other, any one circle of the series representing a cutting edge 15 of the die.

15 Referring to the drawing, 1, 2, 3, and 4 represent a series of concentric circles. Of the circles designated by the numeral 1 there are four in number and they are so arranged that 20 any one of them is described tangent to its adjacent two circles 1, the tangent points be-

ing ninety degrees apart. This arrangement results in the formation between the four tangent points of the circles 1, of a four-sided figure 5 whose sides are made up of the arcs 25 of the four circles 1, the length of each arc being ninety degrees. Within the four-sided design 5 are described concentric with the circles 1 four smaller intersecting arcs 6 resulting in the formation of a smaller four-sided 30 figure within the figure 5.

Having described my invention, what I claim is—

The design for a die for cutting dough, substantially as set forth. 35

In testimony whereof I affix my signature in the presence of two witnesses.

JOHN JACOB PFENNINGER.
